W. GRAHAM-BARNETT

HAIR SHIELD

Filed March 26, 1926

UNITED STATES PATENT OFFICE.

WILLIAM GRAHAM-BARNETT, OF NEW YORK, N. Y.

HAIR SHIELD.

Application filed March 26, 1926. Serial No. 97,554.

My invention relates to a new and improved hair and scalp shield.

One of the objects of my invention is to devise a new and improved shield which will be adapted to protect the hair and scalp of a person during a curling operation or during any operation in which heat or steam is applied to the hair.

Another object of my invention is to devise a form of shield which will be especially adapted for use in connection with hair curlers of any type.

Another object of my invention is to devise a shield which can be quickly applied and removed either before or after curlers have been applied to the hair and which will furnish maximum protection to the roots of the hair and to the scalp and with a minimum of discomfort.

Another object of my invention is to provide a shield with a positive lock that will stay in position as placed and which cannot be forced open either through accident or through the action of the hair regaining its natural position after having been compressed and in this way prevent any steam from reaching the scalp.

Another object is to provide a shield which will not readily warp when subjected to the action of heat or steam. This is attained by reason of the fact that during the time the shield may be subjected to the action of the heat or steam, one portion of the shield is locked between two other portions which are securely riveted together.

Another object is to provide a shield with a flat instead of round or oval opening, the hair thus being compressed in the correct shape for winding round the curler.

Other objects of my invention will be set forth in the following description and drawings which illustrate a preferred embodiment thereof, it being understood that the above general statement of the objects of my invention is intended merely to generally explain the same, and not to limit it in any manner.

Fig. 1 is a top view of my improved shield.

Fig. 2 is a sectional view on the line 2—2 of Fig. 1.

Fig. 3 is a view similar to Fig. 1 but showing the shield in the open position.

Fig. 4 shows how the shield is applied to a lock of hair before the curler is applied.

Fig. 5 is a perspective view showing how

the shield is applied to the root or base of a lock of hair after the curler has been applied.

Fig. 6 is a perspective view showing the shield in the locked position and also showing a curler in position.

The shield comprises a body portion 1 made of three pieces of fibre or any other suitable material which are connected by means of rivets 2. A catch 5 is pivoted to the body portion 1 by means of a pin 6 and it is adapted to enter the space between the two outer members of the body portion 1. As shown in Fig. 3, the catch 5 is provided with a stop shoulder 7 and with a series of ratchet teeth 8. A spring wire 4 is connected to the body portion 1 by means of pin 3 and the free end of the spring 4 is bent so that it can move within the slot 9 of the body portion 1. The free end of the spring 4 is adapted to engage the ratchet teeth 8 end to prevent the catch 5 from being withdrawn from the body portion 1. However, the catch 5 can be forced into proper position by merely pressing thereon, and said catch 5 can also be released whenever desired by merely moving the free end of the spring 4 away from the ratchet teeth 8.

In order to apply the shield to the roots or base of a lock of hair, it is merely necessary for the operator to hold the member 5 and to press the body portion 1 into position. The shield is then substantially closed, as it is then substantially in the position shown in Fig. 1, save for the space occupied by the lock of hair, and this efficiently protects the scalp of the user and the roots of the lock of hair which is being treated.

It is preferable to first apply the curler C to the hair H as shown in Fig. 5 before securing the shield in proper position, and the curler C then occupies the position shown in Fig. 6. The curler C may be of any suitable type and I have merely generally illustrated one of the well known types.

The shield prevents the live steam which is customarily used for curling hair, from affecting the roots of the hair or from injuring the scalp of the user. It also minimizes the danger of entangling stray hairs in any portion thereof, which would cause considerable discomfort to the person whose hair was being treated. The construction of the shield also enables the operator to press

the two parts together very tightly, as the manipulation of the shield is very simple and convenient.

I have shown a preferred embodiment of 5 my invention, but it is clear that numerous changes and omissions could be made without departing from its spirit.

Thus, while I have stated that the parts 10 of the shield may be made of any suitable fibre, the shield may be made of any suitable material, which is preferably a poor conductor of heat.

I claim:—

1. In combination, a hair curler having 15 a spirally wound lock of hair connected thereto and a hair shield free from said curler and located intermediate the base of the lock of hair and the adjacent end of the curler, the said hair shield comprising two 20 connected and relatively movable portions and releasable locking means adapted to hold the two portions of the hair shield together to tightly grip the base of the lock of hair.

2. In combination, a hair curler having 25 a spirally wound lock of hair connected thereto and a hair shield free from said curler and located intermediate the base of the lock of hair and the adjacent end of the curler, said hair shield comprising a body 30 portion, a catch pivotally connected thereto,

and releasable locking means adapted to connect the free end of the catch to the body portion of the hair shield.

3. A hair shield comprising a body portion, a catch pivotally connected thereto, 35 the free end of the said catch having a plurality of ratchet teeth, and movable spring means connected to the said body portion and adapted to releasably engage the said ratchet teeth. 40

4. A hair shield comprising a body portion having a catch pivotally connected thereto, the said body portion being provided with a slot, a spring connected to the said body portion and having a bent-in end projecting into the said slot, a catch pivoted to the said body portion at a point spaced from the said slot, the said catch having a plurality of ratchet teeth at the free end thereof, the said ratchet teeth being adapted to contact with the bent-in end of the said spring when the said catch is moved towards the said body portion, so that the bent-in end of the said spring engages the said teeth. 45

5. A device according to claim 4 in which 50 the said catch has a stop shoulder adjacent the said ratchet teeth.

In testimony whereof I affix my signature.

WILLIAM GRAHAM-BARNETT.
